UNITED STATES PATENT OFFICE.

JAMES P. HIGH AND HARRY C. RATHBUN, OF FAIRVIEW, OKLAHOMA.

OIL-BURNING STOVE.

1,137,970.

Specification of Letters Patent.

Patented May 4, 1915.

Application filed June 16, 1914. Serial No. 845,471.

To all whom it may concern:

Be it known that we, JAMES P. HIGH and HARRY C. RATHBUN, citizens of the United States, residing at Fairview, in the county 5 of Major and State of Oklahoma, have invented a new and useful Oil-Burning Stove, of which the following is a specification.

The invention relates to improvements in 10 oil burning stoves.

The object of the present invention is to improve the structure and efficiency of oil burning stoves, more especially that shown and described in our application Serial No. 15 833,398, filed April 21, 1914, and to equip the stove with means for confining the heat to a greater extent within the stove, to render the latter more comfortable for cooking during the summer time.

20 A further object of the invention is to arrange the oil tank in a comparatively cool position, where it will require less air pressure and thereby render the stove safer and less expensive.

25 With these and other objects in view the invention consists in the construction and novel combination of parts hereinafter fully described, illustrated in the accompanying drawings, and pointed out in the claims 30 hereto appended, it being understood that various changes in the form, proportion, size and minor details of construction, within the scope of the claims, may be resorted to without departing from the spirit or sacrificing any of the advantages of the invention.

In the drawings:—Figure 1 is a vertical sectional view of an oil burning stove constructed in accordance with this invention. 40 Fig. 2 is a plan view of the same.

Like numerals of reference designate corresponding parts in both the figures of the drawings.

In the accompanying drawings, in which 45 is illustrated the preferred embodiment of the invention, the stove casing comprises in its construction upper and lower substantially cylindrical telescoping sections 1 and 2 constructed of sheet metal or other suitable material and adjustable to vary the distance between the top of the stove and the burner hereinafter described, whereby the heating effect may be varied to adapt the stove for different cooking operations, as 50 explained in the aforesaid application. The lower section 2, which has an opening ex-

tending entirely through it, is provided at its lower end with an enlarged base 3 of cylindrical form, consisting of a vertical wall and a horizontal connecting flange or portion 4 extending inwardly from the upper edge of the said vertical wall to the lower edge of the lower cylindrical section 2 of the casing. The base, which is provided at an intermediate point with air 60 inlet openings 5, has a lower outwardly flared downwardly extending supporting flange 6 adapted to rest upon a supporting surface.

The outwardly extending base 3 supports 70 an annular tank 7, designed to contain oil or other liquid fuel and consisting of inner and outer vertical concentric walls and top and bottom connecting walls. The tank 7 is arranged in spaced relation with the 75 lower section of the casing to provide an intervening air space 8, which is open at the top, and the supporting flange or portion of the base is provided at the air space with openings 9 to permit a portion 80 of the air entering the inlet openings 5 to pass directly upward through the space between the oil tank and the lower cylindrical section 2 of the casing. The oil tank terminates short of the upper end of 85 the lower section 2 of the casing, which is jacketed to the head of the oil tank to confine the head within the stove for the purpose of protecting the fuel tank and for rendering the stove more comfortable for 90 cooking during the summer time. The jacket consists of a lining 10 of asbestos or similar material surrounding the major portion of the lower section 2 of the casing, and arranged within a cylindrical sleeve 11 95 constructed of sheet metal or other suitable material and provided at the top with a flange 12. The sleeve extends upwardly from the flange or connecting portion 4 of the base and the top flange 12 fits against the section 2 and covers the upper edge of the asbestos lining. The jacket and the air space render the fuel tank comparatively cool, and prevent any radiation of heat at this portion of the stove.

100 The oil or other fuel contained within the tank is forced outwardly therefrom by air pressure, and is delivered to a combined generator and spreader 13 through a supply pipe 14 located within the base 3 and consisting of an upper leg or branch 15, a lower leg or branch 16, and a vertical connecting 110

branch or portion 17. The supply pipe is provided at one end of the upper branch portion with a controlling valve 18, which is connected with the adjacent portion of the oil tank by a threaded nipple 19 piercing the flange 4 of the base and the bottom of the said tank. The combined generator and spreader 13, as explained in the aforesaid application, preferably consists of a relatively thin hollow disk forming a shallow interior chamber 20 and adapted to present a relatively large amount of heating surface to the liquid fuel for vaporizing the same. The combined generator and spreader receives right and left hand threaded portions 21 and 22 of the upper leg or branch 15 of the supply pipe, and is adapted to be partially rotated to arrange it either in a horizontal position, as shown in full lines in Fig. 1 of the drawing, or in a vertical position, as indicated in dotted lines in the said figure. By this construction the generator is adapted to be arranged for spreading or flaring the flame of the burner, and also to permit the flame to pass directly upward at the center. The lower leg or branch 16 of the supply pipe constitutes a burner tube and is provided with a jet aperture 23 located centrally of the base at a point directly beneath the combined generator and spreader. A starting or priming cup of any desired construction may be placed beneath the lower leg or burner tube, which is arranged above the plane of the lower edge of the supporting flange 6 to permit such a starting or priming cup to be used.

The tank is provided with a filling aperture 24 having a closure plug 25 carrying a tube 26 of small diameter and an air valve 27 similar to that with which an ordinary pneumatic tire tube is equipped. The tube 26, which consists of a hollow wire or the like, extends from the closure plug to a point adjacent to the bottom of the tank, so that the air forced into the tank will be delivered to the same at the bottom thereof, and will be caused to pass upward through the liquid fuel, which retains a certain amount of the air as the same is pumped into the tank. This results in a better quality of gas, and the air also prevents a vacuum from forming within the tank. By arranging the tank above the plane of the burner, the oil is adapted to feed to the same by gravity, thereby reducing the air pressure and enabling the stove to operate with a comparatively low pressure within the fuel tank.

The upper section 1 of the casing is provided with lateral outlet openings 28 located a short distance below the top wall 29, constructed as shown and described in the aforesaid application, and consisting of a disk or plate suitably secured at its periphery to the vertical sides or walls of the upper section. The top 29 is provided with outlet openings

30 and it has a central opening 31 for the reception of a pivot 32 of an upper adjustable plate or disk 33. The said top 29 is also provided with exterior protuberances 34 adapted to support the upper adjustable plate 33 in spaced relation with the top 29. The central pivot 32, which is suitably secured to the upper adjustable plate, extends downwardly from the center thereof and is provided with a laterally extending lug or projection 35 adapted to be passed through a notch or recess 36 of the top 29 at one side of the central opening 31. After the lug has been passed through the notch or recess, the plate 33 is partially rotated to carry the lug 80 away from the said notch or recess. The upper section 1, which is slidably upwardly and downwardly on the exterior of the lower section, is provided with opposite vertical slots 37, and has recesses or branches 38 extending from the slots and adapted to be engaged by lugs or projections 39 mounted on and extending horizontally from the lower section. The vertical slots 37 extend upwardly from the lower edge of the upper section and the lugs or projections and recesses provide an adjustable interlocking connection between the upper and lower sections 1 and 2 of the casing. The upper section is equipped with a hinged bail 40 having a suitable handle and adapted to permit the stove to be conveniently carried. The bail, when not in use, is adapted to swing below the top of the stove. No claim is made in the present application to the particular construction of the upper section of the casing or to the combined generator and spreader, as this construction forms a part of the subject matter of and is claimed in the aforesaid application.

What is claimed is:—

1. A stove of the class described including a casing comprising upper and lower telescopic sections provided at their adjacent ends with means for adjustably connecting them, a hollow base supporting the casing and projecting outwardly at the bottom of the lower section, and a fuel tank mounted upon the base and surrounding the casing, said tank being arranged in spaced relation with the casing and terminating short of the upper end of the lower section thereof.

2. A stove of the class described including a casing, a base supporting the casing and consisting of an outwardly extending horizontal flange and a vertical wall connected with the said flange at the outer edge thereof and provided with openings, and a fuel tank mounted upon the base in spaced relation with the casing and surrounding the same, said fuel tank being supported upon the base and the flange thereof being provided with openings communicating with the interior of the base and the space between the casing and the tank.

3. A stove of the class described including a casing, a fuel tank surrounding the casing in spaced relation therewith to provide an intervening air space, a base having a horizontal flange extending across the space between the casing and the fuel tank at the bottom thereof and supporting the said tank, a lining of non-heat conducting material surrounding the casing at the said space, and a metallic sleeve incasing the said mate-

rial and arranged in spaced relation with the fuel tank.

In testimony, that we claim the foregoing as our own, we have hereto affixed our signature in the presence of two witnesses.

JAMES P. HIGH.
HARRY C. RATHBUN.
